UNITED STATES PATENT OFFICE

99,020

DESIGN FOR A SCALE RECORDER HOUSING

Harlan A. Hadley, St. Johnsbury, Vt., assignor to
E. and T. Fairbanks and Company, St. Johnsbury, Vt., a corporation of Vermont

Application September 7, 1935, Serial No. 58,837

Term of patent 7 years

To all whom it may concern:

Be it known that I, Harlan A. Hadley, a citizen of the United States, residing at St. Johnsbury, in the county of Caledonia and State of Vermont, have invented a new, original, and ornamental Design for a Scale Recorder Housing, of which the following is a specification, reference being had to the accompanying drawing, forming part thereof.

Figure 1 of the drawing is a perspective view of a scale recorder housing showing my new design. Figure 2 is a top plan view thereof.

I claim:

The ornamental design for a scale recorder housing, as shown.

HARLAN A. HADLEY.
